DESIGN FOR A FOUR-ENGINE TRANSPORT AIRPLANE

Frank R. Canney and Lysle A. Wood, Seattle,
Wash., assignors to Boeing Aircraft Company,
Seattle, Wash., a corporation of Washington

Application November 16, 1936, Serial No. 65,949

Term of patent 7 years

To all whom it may concern:

Be it known that we, Frank R. Canney and Lysle A. Wood, both citizens of the United States of America, and both residing at Seattle, in the county of King and State of Washington, have invented a new, original, and ornamental Design for a Four-Engine Transport Airplane, of which the following is a specification, reference being had to the accompanying drawings, forming part thereof.

Figure 1 is a plan view of the airplane, showing our new design.

Figure 2 is a front elevation of the same in flight.

Figure 3 is a side elevation of the airplane in flight.

We claim:

The ornamental design for a four-engine transport airplane, substantially as shown.

FRANK R. CANNEY.
LYSLE A. WOOD.
